UNITED STATES PATENT OFFICE.

JEAN ZWICKY, OF FARNHAM ROYAL, ENGLAND.

OIL-GAS APPARATUS.

Application filed December 21, 1925, Serial No. 76,877, and in Great Britain December 19, 1924.

This invention relates broadly to apparatus for producing gas from liquid or powdered fuel by spraying and partially burning the fuel in air, the heat thereby engendered converting the remainder of the fuel or the bulk thereof into the form of combustible gas which is delivered from the apparatus for use in heating, in internal combustion engines, and other purposes. One form of apparatus of the type in question is that disclosed, for example, in the British patent to Hackford, No. 217,613.

The purpose of the invention is to provide for the adequate preheating of the fuel, for the proper and automatic regulation of the proportion of fuel to air, for the convenient starting of the apparatus and for easy accessibility of parts likely to need attention. The means by which these purposes are attained may be explained by reference to a construction of apparatus embodying the invention illustrated in the accompanying drawings, and are defined in the appended claims.

In these drawings—

Figure 1 is a longitudinal vertical section of an apparatus designed for generating gas from oil.

Figure 2 is an elevation of the left-hand end.

Figure 3 is a central horizontal section through the housing that contains the partial-gasification means.

Figures 4 and 5 are axial sectional elevations of modified gasification means designed for use with coal or oil, or coal and oil.

Figure 6 is an enlarged vertical section of an additional control device that may be employed with the apparatus.

Figure 7 is a vertical section through the housing of Fig. 1.

Figure 8 is a view similar to Fig. 3, but showing the pilot jet in lighting position.

This figure also shows the tank for supplying oil to the pilot jet, though such tank is actually located above the plane of the section.

The chamber wherein the partial combustion of the fuel and the production of the gas take place is conveniently in the form of a horizontal metal cylinder 1, with a thick lining 2 of refractory material, and with an outlet 3 in any desired position around the cylinder similarly lined. At one end the oil generating chamber is closed by a metal

door 4 carrying a refractory block 5 of truncated conical form which fits the coned end of the refractory lining 2. The block 5 is attached to the door 4 by means of a plate 60 of metal 6 embedded in the block and bolted to the door. The door is hinged upon the chamber 1 to open in any desired direction, and is held closed by any convenient means shown as a number of catches 7 engaging hooks on the chamber. Asbestos tape or a corrugated metal ring 8 ensures a gas-tight joint between the door and the gasifying chamber. The chamber is further surrounded by asbestos or other lagging 9 enclosed within a planished steel casting 10 secured by bands not shown.

The air and oil supply, together with the means for preheating the air and oil, and for regulating their admission, and also the means for initially heating the oil and air to start the process, are located at the other end of the chamber 1 in a box or housing 11 bolted to a flange upon the chamber. An annular oil preheating chamber 12 is secured in the housing and divides its central portion forming the air inlet 13 from its outer portion forming the annular air conduit 14; said preheating chamber also providing a connection between these two parts 85 13 and 14 in which is located the air valve 15. The annular air conduit 14 has a flue 16 leading to the outer air, and this can be closed by a valve 17. Air is supplied to the conduit under pressure by any suitable fan or blower indicated diagrammatically and on a smaller scale at 69 through a heat exchanger 18 which is an annular passage encircling the gas outlet 3, said passage 18 having an inlet at 19. In the air conduit 14 there is also a change-over valve 20 (Figure 2) which in one position cuts off the conduit from its connection to the heat exchanger, and in another position forms a partition across the conduit. Beside this is 95 an air regulator 21 by which the opening between the heat exchanger and the air conduit may be regulated as desired. Means are provided for initially heating the air conduit 14 and oil preheating chamber 12. Where steam or hot water is available, suitable pipes and control cocks for the conveyance of these heating fluids may be provided for this purpose; in other cases means are provided for introducing fuel into the air conduit 14 and burning it for the purpose 105 of starting the apparatus. The construction

illustrated is designed to use paraffin as a starting fuel, and for this purpose the air conduit 14 is provided with an air door 22 and a fuel tray 23 with a filling opening 24 through which the paraffin may be introduced.

The fuel jet 25, provided with a renewable nipple 26 and with fixed and movable deflectors 27, 28, for the guidance of the air, is attached to a cover plate 29 which closes a central opening in the outer wall of the air channel which connects the conduit 14 to the air inlet 13. This plate is secured in position by a cross bar 30 hinging on the stud 31 and clamped by a nut 32. In a central bore in the cover plate there slides the oil control valve 33, the stem of which has a number of annular grooves in it to hinder leakage of oil along it. The valve seating is at the inner end of the jet 25. The control valve 33 is connected with the air valve 15 through a lever 73 pivoted on the stud 31. Oil reaches the valve and jet from the oil preheating chamber 12 through a passage formed partly in a detachable cross connection 34 (Figure 3). In another part of this passage is the spring-pressed oil cut-off valve 35, the stem of which extends to the wall of the cross connection 34, so that when the cross connection is secured in position the valve is pressed off its seating against the action of its spring. The oil supply pipe and main oil valve are shown at 36 and 37 (Figure 2), and a drain cock 38 for the oil preheating chamber at 38. Any oil which may escape from the passage to the jet 25 is collected at 39 (Figure 1) and led by pipe 40 to a drain cone 41 where its passage can be observed. Another pipe 42 closed by a cock 43 enables oil which may collect in the air inlet 13 to be drained into the cone 41. A third pipe 44 leading to the drain cone carries oil which may leak past or may be run out through the drain cock 38.

At 45 is a small paraffin tank from which oil is led by a pipe 45' to an adjustable pilot jet 46, which may be moved inward into the position represented in Fig. 8, where it may be ignited by a torch introduced through the passage 47 which normally is closed by the plate 48. This is not essential; the apparatus may be started by filling the oil preheating chamber 12 with paraffin and burning it at the fuel jet 25. A thermometer 49 shows the temperature of the oil and a gauge 50 shows the air pressure.

The apparatus, which operates in a manner broadly similar to that described in the previously mentioned British Patent No. 217,613, is started as follows. By opening the main oil valve 37 the annular oil preheating chamber 12 is filled, and the oil valve is then temporarily closed. The valve 17 is opened and the valve 20 is set in the

position shown in dotted lines in Figure 2 in which it closes the air inlet passage. Some paraffin is placed in the tray 23, the door 22 is opened and the paraffin ignited. When the oil in the chamber 12 has been brought to the requisite temperature as shown by the thermometer 49 the air fan is started, the valve 17 and door 22 are closed, the valve 20 is placed in the open position shown in dot-dash lines in Figure 2, and the valve 21 opened to the required extent. Paraffin is supplied to the pilot jet 46 from the tank 45 and ignited by a torch through passage 47. The main oil valve 37 is again slowly opened. The air passing from the annular chamber 14 to the inlet 13, and which enters the former under pressure, due to the provision of the fan or blower 69, swings open the valve 15 and thereby opens to a greater or less extent the oil control valve 33. The issuing oil is lit by the pilot jet to effect partial combustion and gas production begins. When the oil is being satisfactorily atomized the pilot jet 46 and the movable deflector 28 are withdrawn from the position shown by Figure 8 to that shown by Figure 3 and the supply of paraffin is cut off. In this latter position the deflector 28 is continuous with the fixed stream line deflector 27, which may in some cases be dispensed with, while when thrust forward for starting or during times of light load, it diminishes the inlet area, thus increasing the velocity of the air and assisting atomization.

If it is required to withdraw the oil valve for examination the nut 32 is slackened, the cross bar 30 swung aside and the cross connection 34 removed. The plate 29 carrying the oil valve 33 and the jet 25 can then be withdrawn. Escape of oil is prevented by the automatic closing of valve 35.

To adapt the apparatus for operation on different classes of oil fuel, means may be provided for adjusting the setting of the oil valve 33 corresponding with any given setting of the air valve 15. A suitable means indicated in Figure 1 consists in providing upon the stem 33 a sleeve 70 in which slides the block 71 with which the lever 73 engages, said block being pressed towards the stem 33 by a spring 72. A portion of the member 71 projects beyond the sleeve 70 and has pivoted upon it a cam 74 which may consist of two polygonal plates located one on each side of said member 71 and connected together by the pivot. In the projecting portion of the member 71 is a lateral spring-pressed pin 75 which engages in one or other of a series of recesses 76 in one of the plates 74. By means of the handle 77 the cam may be rotated to cause the pin 75 to engage in any one of the recesses 76 and to hold the cam with any one of its faces (except that to which the handle is fastened) presented to

the sleeve 70. By such movement of the cam the position of the valve 33 corresponding with any given setting of the lever 73 and air valve 15 may be altered. The cam 5 may bear indications showing the setting suitable for the several classes of oil the use of which is contemplated. If this adjustment is not required the end of lever 73 may engage in a recess in the end of stem 33 such 10 as is indicated at 78 in Figure 3.

The apparatus may be used for making gas not only from any kind of oil, whether crude oil, topped oil, or oil residue, but also from solid fuel such as powdered coal, the 15 burner being modified to suit the fuel; and one and the same apparatus may be adapted by the provision of suitable burners for dealing with either oil or coal, or both together. Figure 4 shows the box or housing 20 of such a generator. The oil jet 51, which may be constructed and connected in the manner already described, is surrounded by a coal jet 52, to which the powdered coal may be forwarded by a screw or preferably 25 by an air blast, which may be diverted for the purpose from the main air supply or delivered by a separate blower to the pipe 53. There may be a non-return valve in 30 the pipe 53 as a precaution against back firing, and the proportion of air used to forward the fuel should be too small to form an explosive mixture. In the jet 52 the coal is given a whirling motion by a helical fin 54 upon the oil jet 51. The supply 35 of coal is automatically controlled by a valve 55 connected like the oil valve 56 with the main air valve 57. On its way to the valve 55 the coal may be passed through a preheating chamber such as 18 or 14 40 (Fig. 1).

In case only one kind of fuel is to be employed, either the valve 55 or the valve 56 may be disconnected from the valve 57; or if the producer is intended to operate on 45 coal only the oil valve 51 may be omitted, and the fin 54 secured upon a central stem.

Where two fuel burners are employed it is not necessary that they should be concentric; they may be entirely separate as indicated in Figure 5. In this case the coal jet 58 has an interior helical fin 59. The oil jet 79 may be constructed substantially as described with reference to Figure 1 the oil passing to it from supply pipe 80 through 55 valve 81, preheating chamber 12 and valve 33.

An auxiliary automatic means of control which may be used to prevent any undue rise of pressure either within the producer or 60 in the distribution system is shown in Figure 6. It is built upon a pipe branch 60 adapted to be inserted in the pipe by which air is supplied from the blower 69 to the producer; the air supplied by the blower enters branch 60 at 61, and the air passing to the

producer leaves at 62. The control device comprises a valve 63 having a seat in a pipe section 64 having a plurality of lateral outlets 90, through which, when the valve is lifted, the pressure air can escape. The 70 valve is held upon its seat by its own weight and by the weight of a piston 65 and piston rod 66 resting upon it. The piston 65 moves in a cylinder 67 which is connected by a small bore pipe 68 with the outlet side of the 75 producer; the connection may be made to the immediate outlet of the producer, that is to say, between the producer and the filter commonly employed for cleaning the gas, or it may be made to any desired point of the distribution system. If desired two or more such devices as that shown in Figure 6 may be employed, the air supply to the producer passing through all of them, and their respective pipes 68 being connected to different 80 points in the gas mains and distribution system.

The weight of the valve 63 and of the piston 65 and piston rod 66 is sufficient to prevent the valve being lifted by the normal pressure of the air, that is to say by the pressure normally required to propel the air through the producer, filter, and distribution system, acting upon the valve itself, and the pressure in the distribution system or on the outlet side of the producer acting on the underside of the piston 65. But if through choking of the filter, through 85 turning off of taps in the distribution system, or for other reasons, the pressure at the point to which the pipe 68 is connected should rise, the piston 65 will be lifted, freeing the valve 63 which in turn will be raised by the pressure of the air supply beneath, and consequently air will in part escape 90 through the lateral outlets 90 instead of passing to the producer.

Where the power required to supply the necessary air under pressure is of importance, and the blower can be conveniently controlled, as when it is driven by an electric motor, movement of the piston 65 may be utilized to govern the motor so as to lessen the supply of air when the demand on the producer is small.

I claim:

1. In a partial-combustion oil-gas-producing apparatus, an air passage; a liquid fuel jet surrounded by said passage; an annular liquid fuel chamber encircling the air passage; a passage leading from the fuel chamber to the jet for feeding liquid fuel to said jet to be ignited at the mouth thereof; means for supplying heated air to the air passage to preheat the fuel in the fuel chamber and vaporize the fuel in the jet and to support partial combustion only of the fuel vapors; and valve means for controlling the air supply and the fuel feed.
2. In a partial-combustion oil-gas-produc-

- ing apparatus, an air passage; a liquid fuel jet surrounded by said passage; an annular liquid fuel chamber encircling the air passage; a passage leading from the fuel chamber to the jet for feeding liquid fuel to said jet to be ignited at the mouth thereof; means for supplying heated air to the air passage to preheat the fuel in the fuel chamber and vaporize the fuel in the jet and to support 5 partial combustion of the fuel vapors; separate valves for controlling the air supply and the fuel feed; and means for automatically transmitting the movements of the air valve to the fuel valve so as to obtain a 10 proportionate feed of air and fuel.
3. In a partial-combustion oil-gas-producing apparatus, an air passage; a liquid fuel jet surrounded by said passage; an annular liquid fuel chamber encircling the air passage; a passage leading from the fuel chamber to the jet for feeding liquid fuel to said jet to be ignited at the mouth thereof; means for initially preheating the air passage and the fuel chamber so as to vaporize the fuel 20 in the jet and to support partial combustion of the fuel vapors in starting the apparatus; means for thereafter supplying heated air continuously to the air passage to maintain such vaporization and partial combustion; and valve means for controlling the air supply and the fuel feed.
4. In a partial-combustion oil-gas-producing apparatus, an air passage; a liquid fuel jet surrounded by said passage; an annular liquid fuel chamber encircling the air passage; a passage leading from the fuel chamber to the jet for feeding liquid fuel to said jet to be ignited at the mouth thereof; an annular air conduit encircling the 30 fuel chamber and provided with an inlet; a heater in said conduit adjacent its inlet to heat the air entering therethrough; means for conducting the heated air from the conduit to the air passage so as to vaporize the fuel in the jet and to support partial combustion of the fuel vapors in starting the apparatus; means for thereafter supplying heated air continuously to the air passage to maintain such vaporization and partial 40 combustion; and valve means for controlling the air supply and the fuel feed.
5. In a partial-combustion oil-gas-producing apparatus, an air passage; an annular liquid fuel chamber encircling the same; a liquid fuel jet surrounded by the air pas- 50 sage; a passage leading from the fuel chamber to the jet to feed liquid fuel to said jet to be ignited at the mouth thereof; means for supplying heated air to the air passage to heat both the fuel chamber and 60 the jet and vaporize the fuel in the latter and to support partial combustion of the fuel vapors; separate valves for controlling the air supply and the fuel feed; means for automatically transmitting the movements 65 of the air valve to the fuel valve to obtain a proportionate feed of air and fuel; and means for adjusting the position of the fuel valve for any given position of the air valve.
6. In a partial-combustion oil-gas-producing apparatus, an air passage; a liquid fuel jet surrounded by said passage for discharging fuel to be ignited at the mouth of the jet; a liquid fuel chamber encircling the air 70 passage; a feed passage leading from the fuel chamber to the jet and including a detachable section; means for supplying heated air to the air passage to preheat the fuel in the fuel chamber and vaporize the 75 fuel in the jet and to support partial combustion of the fuel vapors; and a valve in the fuel passage which is held open by said section when the latter is in place but which is automatically closed when the section is 80 detached so as to shut off the feed to the jet.
7. In a partial-combustion oil-gas-producing apparatus, a liquid fuel jet; an air passage surrounding the jet; a chamber for the 85 liquid fuel surrounding the air passage and connected to said jet; an annular air conduit encircling said fuel chamber and leading to said passage; and means for supplying liquid fuel and air to the fuel chamber 90 and air passage respectively.
8. In a partial-combustion oil-gas-producing apparatus, a housing; a liquid fuel jet, an air passage, a liquid fuel chamber, and an air conduit leading to said passage, said 100 elements being arranged successively in concentric relation to one another in said housing; and a door in said air conduit for the introduction of fuel to be ignited inside the conduit to initially preheat the liquid 105 fuel in the fuel chamber.

In testimony whereof I have signed my name to this specification.

JEAN ZWICKY.
